(Cl. D62—4)

To all whom it may concern:

Be it known that I, Lawrence H. Wilson, a citizen of the United States, residing at Detroit, in the county of Wayne, State of Michigan, have invented a new, original, and ornamental Design for a Dehumidifier, of which the following is a specification, reference being had to the accompanying drawings, forming a part hereof.

Fig. 1 is a front elevational view of a dehumidifier, showing my new design;

Fig. 2 is a top plan view thereof;

Fig. 3 is a side elevational view;
Fig. 4 is a sectional view indicated by line 4—4 of Fig. 1; and

Fig. 5 is a fragmentary sectional view indicated by line 5—5 of Fig. 2.

I claim:

The ornamental design for a dehumidifier, as shown.

LAWRENCE H. WILSON.
